UNITED STATES PATENT OFFICE.

GEORGE C. PYLE, OF INDIANAPOLIS, INDIANA, ASSIGNOR TO THE NATIONAL ELECTRIC HEAD LIGHT COMPANY, OF SAME PLACE.

LUBRICATOR.

SPECIFICATION forming part of Letters Patent No. 450,424, dated April 14, 1891.

Application filed January 21, 1890. Serial No. 337,604. (No model.)

To all whom it may concern:

Be it known that I, GEORGE C. PYLE, a citizen of the United States, residing at Indianapolis, in the county of Marion and State of 5 Indiana, have invented certain new and useful Improvements in Lubricators, of which the following is a specification.

My said invention relates to that class of devices known as "displacement-lubricators;" and it consists in so constructing and arranging such a lubricator that it will form a convenient and economical device connected with or embodied in the engine with which it is used, as will be hereinafter more 15 particularly described and claimed.

Referring to the accompanying drawings, which are made a part hereof, and on which similar letters of reference indicate similar parts, Figure 1 is a central vertical sectional view of a multiple-cylinder engine embodying my said invention on the dotted line 1 1 in Fig. 2, and Fig. 2 a similar view on the dotted line 2 2 in Fig. 1.

In said drawings, the portions marked A 25 represent the casing of the engine; B, the cylinder; C, the crank or wrist pin; D, the reservoir or tank for the oil, and E the pipe or conduit leading from near the top of said tank or reservoir down through its bottom to 30 a point adjacent to the part to be lubricated.

While the engine illustrated embodies some other improvements, (not, however, fully shown,) which are the subject-matter of another application, Serial No. 314,968, for Letters Patent, neither the casing A, cylinder B, nor wrist-pin C is peculiar to my present invention further than that the casing incloses a space into which the exhaust-steam enters, and from which a small portion of exhaust- 40 steam is adapted to pass up through the small pipe E, as will be presently explained.

The reservoir D is shown as being formed by connecting the side walls of two cylinders in the upper half of the engine by a partition 45 b, which closes what would otherwise be an open space between them and forms the bottom to the reservoir. In the top of said reservoir, just above the upper end of the pipe, a hand-hole is formed, which is closed by a 50 screw-plug d', through which hand-hole the

reservoir may be filled with oil or other lubricant; or access may be had thereto for the purpose of cleaning it. Leading out from the bottom of said reservoir to the outside is a pipe or tube containing a cock d², by which 55 the oil or other lubricant may be drawn off when desired, and by which the water or other fluid which during the operation of my invention fills the lower portion of the reservoir may be discharged therefrom. 60

The pipe or conduit E extends from near the top of the tank or reservoir down through its bottom (in the construction shown) to a point near the part to be lubricated, which in the structure shown is the crank or wrist pin. 65 Said conduit is shown as a plain pipe open at both ends, and is preferably located in the central portion of the tank or reservoir. It is shown as being straight; but it may obviously be bent when it is necessary to carry 70 the lubricant to a point different from that immediately below the reservoir.

The operation of my said invention is as follows: The tank or reservoir D is filled with oil or other suitable lubricant to the level of 75 the top of the pipe or conduit E. Provision is then made for the gradual continual introduction of a small quantity of water or other equivalent fluid, and the lubricant, being lighter than the water, will rise thereon and 80 flow out through the pipe E to the point of discharge, where it drops onto the bearing or part to be lubricated. I utilize the exhaust-steam to produce the water. The space inside the casing A is filled with the exhaust- 85 steam in the operation of the engine shown, and a small quantity of this steam continually finds its way up the pipe E into the interior of the tank or reservoir D, where it condenses (principally on the under surface 90 of the upper wall thereof) and produces the water, which, being heavier than the oil, goes to the bottom of the reservoir, raising the oil and causing it to flow into the pipe E and through it to the point to be lubricated, as 95 before described.

By a proper adjustment of the parts, particularly of the size of the tube E, exactly the quantity of lubricant can be caused to be discharged onto the bearing that is required for 100

the purpose, and this quantity will vary somewhat under the conditions described as the speed of the engine varies, for when the engine is running at a higher speed it of course 5 exhausts more steam, and the quantity of exhaust-steam in the interior of the casing is therefore greater, and a somewhat greater quantity will find its way up to the tube E than when the pressure is less. This device 10 thus provides for a continual automatic lubrication of the wrist-pin or other part at all times, which is especially desirable in structures of the character shown, where the point to be lubricated is inclosed by a casing, and 15 therefore difficult of access.

Having thus fully described my said invention, what I claim as new, and desire to secure by Letters Patent, is—

1. The combination, with an engine, of a 20 reservoir or tank formed integral therewith, an open space into which exhaust-steam enters, and a small pipe or tube leading from said open space to the interior of said tank or reservoir, whereby when said tank or reservoir is filled with a lubricant it may be 25 gradually discharged onto the part to be lubricated, substantially as set forth.

2. The combination, with an engine, of a 30 tank or reservoir for a lubricant, forming a part of the structure of the engine and arranged above its wrist-pin, a small pipe leading from a point vertically above the path of said wrist-pin through the bottom of said reservoir into its interior, and means whereby 35 a fluid heavier than the lubricant may be in-

troduced into and withdrawn from said reservoir.

3. The combination, with a multicylinder engine, of a tank or reservoir for a lubricant arranged between two of the cylinders, the 40 walls of which are partially formed by the sides of the said cylinders, said reservoir being arranged above the wrist-pin of the engine, a small pipe leading from the space above said wrist-pin through the bottom of 45 said reservoir to its interior, and a casing surrounding said space into which the exhaust-steam is discharged, whereby in operation said steam will ascend said pipe and displace the lubricant in said reservoir, causing it to 50 flow down said pipe and drop onto said wrist-pin or the bearings thereto, said several parts being arranged and operating substantially as shown and described, and for the purposes specified.

4. The combination, with an engine, of a 55 lubricator the reservoir whereof is formed integrally with the structure of the engine and is located above the point to be lubricated, and a discharge-pipe leading from said reservoir, the discharging-orifice of which is above the point to be lubricated, substantially as shown and described.

In witness whereof I have hereunto set my hand and seal, at Indianapolis, Indiana, this 65 25th day of November, A. D. 1889.

GEORGE C. PYLE. [L. S.]
